UNITED STATES PATENT OFFICE.

GUSTAV A. KRUTTSCHNITT, OF IRVINGTON, NEW JERSEY.

DESIGN FOR A BOX.

No. 39,682.

Specification for Design.

Patented Dec. 8, 1908.

Application filed April 15, 1908. Serial No. 427,284. Term of patent 7 years.

To all whom it may concern:

Be it known that I, GUSTAV A. KRUTTSCHNITT, a citizen of the United States, residing in Irvington, county of Essex, and State of New Jersey, have invented a new, original, and ornamental Design for a Box, of which the following is a specification, reference being had to the accompanying drawings, forming part thereof.

In the drawings, Figure 1 represents a top plan; and Fig. 2 a bottom plan of the box.

The leading and characteristic features of my box are the representation of an old shoe, the toe of which is represented as broken and

torn and the upper of which is represented as being badly creased and worn. The sole of the shoe is hobnailed around its edge,— and the heel is represented as corrugated, said heel being the lid of the box through which matches may be inserted and extracted.

I claim:

The ornamental design for a box, as shown and described.

GUSTAV A. KRUTTSCHNITT.
